UNITED STATES PATENT OFFICE.

HENRY H. DANIELS, OF CINCINNATI, OHIO.

COMBINATION-PADLOCK.

SPECIFICATION forming part of Letters Patent No. 431,336, dated July 1, 1890.

Application filed June 12, 1889. Serial No. 313,991. (Model.)

To all whom it may concern:

Be it known that I, HENRY H. DANIELS, a citizen of the United States of America, and a resident of the city of Cincinnati, in the 5 county of Hamilton and State of Ohio, have invented certain new and useful Improvements in Combination-Padlocks, of which the following is a specification.

The several features of my invention and 10 the various advantages resulting from their use, conjointly or otherwise, will be apparent from the following description and claims.

In the accompanying drawings, forming 15 part of this specification, Figure 1 represents a side elevation of a padlock embodying my invention. Fig. 2 is a vertical central section of the said padlock, taken in the plane passing through the longitudinal center of the staple, those portions of the staple exterior 20 to the body or shell of the padlock being shown in elevation. Fig. 3 is a top view of the shell of the padlock, the cover or locking-disk which fits down upon said top being removed. Fig. 4 is a vertical central section of 25 the shell of the padlock and the aforesaid cover, the latter being shown separated from the shell, the section being taken through the center of the holes or openings which receive the shanks of the staple. Fig. 5 is a side elevation of the dial-plate, its shank and intervening connections, and the chambers which, 30 respectively, inclose the tumblers of the lock, only that portion of the dial-shank which projects above the said tumblers being shown. Fig. 6 is a top view of one of the disks and 35 its tumbler and of the tumbler-chamber and the adjacent portion of the shell of the padlock surrounding said chamber. Fig. 7 is a top view of one of the tumblers detached. Fig. 8 is a top view of one of the disks. Figs. 40 9, 10, 11, and 12 are bottom views of the respective disks employed in the combination. Fig. 13 represents a view in perspective of the shank of the indicating-dial, and showing 45 on the shank the respective studs or carriers for respectively rotating the tumblers. Fig. 14 is a top view of the disk, whose bottom is shown in Fig. 11.

A indicates the shell of the padlock. This 50 shell is preferably cylindrical in shape.

B indicates the staple provided with shanks b' b', said shanks entering the padlock.

The shell A of the padlock is interiorly provided with a partition a'. It is also provided with a cover D. This cover is secured 55 in any suitable manner in the upper end of the padlock in the recess E of the shell. The preferred means for securing this cover in position consists of a screw-thread d³, formed on its periphery and engaging a corresponding screw-thread on the interior of the recess E of the shell A. The partition a' is also provided with openings a² a², and the cover D is provided with openings d' d'. Through 60 these openings a² d', respectively, pass the shanks b' b' of the staple B.

The index dial or disk C is located at that 65 end of the padlock which is opposite where the staple enters, and preferably constitutes, as shown, that end or head of the padlock, 70 and the figures for said combination and for unlocking the padlock are placed preferably upon the peripheral edge of this disk. The disk carries the shank C⁴, which latter passes through the center of the tumbler-disks, tumbler-rings, and tumbler-chambers of the padlock. These disks, tumblers, and tumbler-chambers are prevented from sliding in the 75 cylinder in the direction of the length of the latter by being securely held between the partition a' of the padlock-shell on the one side and the bed or wall C² belonging to the disk C on the other.

The dial-disk C is preferably provided with a shoulder C'. The lower edge of the padlock-shell A rests against the inner face of the dial C, and the shoulder C' of the dial fits closely within the said shell A of the padlock. By these means the padlock-shell A and the dial-disk C are firmly held together 85 and cannot be displaced. That portion of the shank C⁴ which extends above and beyond the tumblers and tumbler-chambers is provided with a screw-thread. This screw-threaded portion of the shank C⁴ passes through the opening a⁴ and projects beyond the partition a'. That portion of the shank C⁴ which thus projects beyond the partition a' receives an annular nut C⁵, which is screwed upon the shank C⁴ and occupies the recess a⁵ in the 90 upper part of the partition a'. To prevent this nut being unscrewed when the dial C is turned to unlock the padlock any suitable means may be employed, the preferred means 95 100

being as follows: The upper side of the circular nut C^5 is provided with grooves C^6 C^6 , radial in their direction, and the upper end of the shank C^4 is likewise provided with the groove C^7 , which latter, when the annular nut is properly turned, is coincident with the grooves C^6 of said nut. A close-fitting key C^9 is then placed in the grooves C^6 C^7 , and thereby prevents the annular nut from turning upon the shank C^4 independently of the latter. In other words, the key C^9 compels the annular nut C^5 to turn with the shank C^4 and prevents the nut from unscrewing from the shank C^4 when the dial C is turned. The number of tumblers employed in the combination-lock of this padlock may be varied from two to any desired number. The number preferably employed is four, and the tumbler-chambers for the tumblers are respectively designated on the drawings by the letters G , H , I , and J . (See Fig. 5.)

Suitable means are employed for preventing the chamber-tumblers from rotating. A novel and convenient means is shown in the drawings. Each of the tumbler-chambers G , H , I , and J is provided at its periphery with a transverse recess or depression S , cut therein, substantially as shown in Figs. 5 and 6. The inner side or wall of the padlock-shell A is provided with a ridge, feather, or equivalent projection S' , parallel to the axis of the shell, and this projection or ridge S' fits into the recess S of the tumbler-chambers. The ridge S' , being stationary, prevents the chambers further rotating within the shell. These chambers, therefore, while being capable of being removed from the shell by sliding laterally within the shell when the dial-disk has been removed, are, when in working position within said shell, stationary therewith. Each tumbler-chamber receives a tumbler K . Each of these tumblers is made substantially alike, and each of them is provided with like novel means, in connection with a central disk of each tumbler, for conveniently and quickly changing the combination of the lock. Each of the tumbler-chambers is recessed at two points on its interior, and each of the tumblers K is likewise recessed at two points f' on its outer edge. One of the recesses f' fits the adjacent recess k' on one side of the shank C^4 of the dial-disk, and the other recess f' fits the other recess k' on the other side of the shank C^4 of the dial-disk. Each of these recesses is preferably of a semicircular form, and the combination of the recess k' and the recess f' forms a circular hole which receives one of the shanks b' b' of the staple B . Each of the shanks b' b' of the staple B is provided with recesses b^2 b^2 , into which the edges of the adjacent tumblers respectively enter, when the staple B is adjusted in the padlock and the latter is locked.

It will be observed that a plane passing through the axes of the holes f' k' will pass to the side of the axis of the shank C^4 , which latter axis may be considered the axis of the

padlock. This arrangement of these holes in relation to the axis of the padlock is intentional, I having invented it for preventing the concave openings f' of the tumblers from coinciding with the openings k' of the tumbler-carriers more than once in an entire revolution of the tumbler. Were this arrangement not present, the openings f' of a tumbler would coincide with the openings k' of the padlock twice in the course of a revolution of a tumbler, thereby allowing the said openings f' of the tumblers to be more readily caused to coincide with the openings k' of the tumbler and the lock to be more readily opened. The lock in such event could be opened on combinations other than the one on which it was set. My novel arrangement of the openings f' k' so that a plane passing through their axes is to one side the axis of the shank C^4 prevents what may be termed "false setting" of the tumblers and the disadvantages resulting therefrom.

For the purpose of enabling the tumbler-chambers to always be adjusted in relation to one another in the proper position, and for retaining them in a proper position in relation to each other after they have been adjusted, I provide two pins k^2 k^2 . Each of these pins is fixed in the lower or end tumbler-chamber J , and is received in holes or openings k^3 in the other tumblers, substantially as shown by dotted lines in Fig. 5 and by solid lines in Fig. 6. By placing the tumblers I H G in their respective order upon the chamber J , the pins k^2 being within the respective holes k^3 of the tumbler-chambers, the tumbler-chambers will be in a proper position relatively to one another, and can only rotate, if at all, together. Their joint rotation is prevented by means of the recess S , heretofore described, and which, when the tumblers are placed within the shell A of the padlock, engages the ridge or feather S' of the said shell A .

In locking and unlocking the lock the tumblers operate in substantially the same manner as do the tumblers of other well-known combination-locks.

The mode and means whereby the combination of dial movements may be changed are novel and exceedingly simple, and permit the combination to be quickly and readily changed. This novel means for changing the combination will now be described. Each of the tumblers is compound, and consists of the annular ring M and the tumbler-disk N . Each of these disks is provided with a stop or abutment n' . These stops n' are of a curved description, concentric with the disk to which they belong, and are of varying length, the longest of the four disks shown, namely, in Fig. 9, being of a complete circle, with the exception of the interval n^2 , which latter in the present instance is of about the width of the opening n^3 in said disk. The ends of these stops or abutments n' , as the dial C and the shank C^4 are turned, respectively come into contact with the respective adjacent studs or

carriers C⁵ on the said shank C⁴. As the stops n' are of different lengths, it is obvious that the disk N (shown in Fig. 12) may, together with its ring F, rotate nearly an entire revolution before its abutment n' comes into contact with the said stud or carrier C⁵ of the shank C⁴ in line therewith. The disk shown in Fig. 11, with its annular ring F, can revolve a less distance before its abutment n' comes into contact with the stud or carrier C⁵ of said shank C⁴. The disk N (shown in Fig. 9) and its annular ring F will be immediately revolved by dial-shank C⁴, as the adjacent carrier or stud C⁵ on the latter will immediately impinge against one or the other ends of the abutments n' of said disk M. Each of the disks is provided with an opening n³, for the purpose of allowing the disks, with their annular rings, when about to be placed upon the shank C⁴, to be passed down said shank and the studs or carriers C⁵ without impediment. These openings n³ n³ will also allow the disks, with their annular rings, to be withdrawn from the shank C⁴ for any purpose desired, and the lock thus to be taken apart. Each of the annular rings F is provided with a series of niches or depressions f², and the spaces between these niches bear any desired figure or character. Each of the disks N is provided with a stud or boss n⁴, adapted to engage in any one of the niches or depressions f² of its respective annular ring F. This stud n⁴ projects from and beyond the periphery of the disk. This stud n⁴ can be placed in any one of the niches f² of the annular ring of the disk N, at the same time fitting closely within the opening in said ring and forming, together with the said ring, a solid compound tumbler. By turning the stud n⁴ to a depression or niche between any two of the figures the point at which the tumbler will be turned during the rotation of the next dial and its shank C⁴ will be altered. In this way the time and point at which the various tumblers will coincide, so as to enable the openings k' in their respective peripheries to coincide with the openings f' of the tumbler-chambers, will be fixed.

In setting the tumblers the following facts must be borne in mind. The preferred mode in which the tumblers are to be marked is shown, and is as follows: One tumbler carries a given number of figures or characters equal to the number of notches f² of the tumbler-ring F. These numbers are placed on the ring. One tumbler, having the disk shown in Fig. 12, carries the odd numbers from 1 to, say, for illustration, 23. The next or second tumbler, having the disk shown in Fig. 11, carries the even numbers from 2 to 24. The next or third tumbler, having the disk shown in Fig. 10, carries the odd numbers from 1 to 23, and the next or fourth tumbler, having the disk shown in Fig. 9, carries the even numbers

from 2 to 24. Each tumbler-disk carries two arrows pointing around the disk in opposite directions. Each of these arrows points to a mark. For turning to the left put that mark of the disk which is indicated by the arrow that points to the left opposite the figure on the tumbler at which it is desired to set the tumbler. By way of illustration, take the first disk. (Shown in Figs. 8 and 12.) This disk, on account of its abutment being a narrow one—viz., substantially a single line—the disk will carry but one mark n⁵, and both of the arrows will point thereto, as shown. Now take the second disk—viz., that shown in Figs. 11 and 14. As its abutment n' is quite wide, two lines n⁵ n⁵ are present on the top of the disk to mark the points where the ends or operating-points of the abutment are on the under side of this disk. Each of these marks has its arrow, indicating by its direction which end of the abutment to choose in setting the tumbler to be properly operated by turning the shank C⁴ of the dial, and the tumbler to a given number on the dial. The marking of the last-named disk as to lines n⁵ n⁵ and arrows is similarly carried out on the succeeding disk of Figs. 10 and 9, the lines n⁵ n⁵ on the one side of the disk respectively coinciding with the respective ends of the abutment on the other side of the disk on which they (said lines) are marked.

The mode in which the tumblers are set and operated is in general as follows: To set the lock, for instance, we will set the first tumbler on No. 1 by setting that mark of the disk of said tumbler designated by the arrow turning to the right on No. 1, which will then correspond to one on the index-dial when turned to the right. Now we will take the second tumbler and set it in a similar manner on 18, turning to the left, which will correspond to 18 on the index-dial when turned to the left. No. 3 tumbler we will set on No. 3, turning the mark on the disk to the arrow to the right No. 3, as we will turn the dial to the right. Now the upper tumbler, always revolving with the dial-plate, stops on any number until the last two tumblers that were set, and therefore always revolving with the dial-plate, there is but one marked disk where to set it. Now that we have the tumblers set, we will turn the dial-plate to the right not less than two revolutions to get the tumblers in position, and stop on No. 1, as we have it set for that. The index-dial is now turned to the left, until the No. 18 thereon is reached, when the dial is stopped. Now we will turn the dial, the third tumbler to the right, and stop on No. 3, and corresponding with the setting of the tumbler. The fourth tumbler, as we have said, revolves all the time with the dial-plate, and is stopped on some number between the last two numbers that have been set. Take No. 10 and stop the dial-plate on No. 10. The tumblers are all now in a position so that the shanks of the staple can be withdrawn. Should the padlock, after

the staple has been withdrawn, be locked by the tumblers being turned so that the holes in the padlock for the reception of the shanks are partly filled by a tumbler or tumblers, the 5 padlock may, by the operation of unlocking aforementioned, be quickly put into condition for the ready insertion therein of the staple. When the padlock is locked, the staple holds together whatever is placed in its 10 grasp, or is passed through it in the manner common to padlocks.

Instead of the screw-thread d^3 on the cover D and the screw-thread on the shell A, other suitable means for securing the cover to the 15 shell may be employed—for instance, a bayonet or lock joint may be employed. It is desirable in all cases to employ means for uniting the cover and shell which shall compel a rotation of the cover in relation to the shell 20 in order to connect the former to or disconnect it from the latter. In this way the insertion of the staple into the padlock will subserve the valuable purpose of locking the cover to the shell by preventing the rotation 25 of the one upon or against the other.

What I claim as new and of my invention, and desire to secure by Letters Patent, is—

1. The shell or casing A, having fixed partition or diaphragm a' , provided with holes 30 $a^2 a^3$ for the reception, respectively, of the respective ends of the shanks of the staple, and the lid or cover D, provided with a screw-thread engaging a screw-thread on the shell above the partition a' , and having the holes 35 $d' d'$ for the reception of the shanks of the staples, the diaphragm a' , furnishing non-rotatable bearings within the shell for the shanks to impinge against, substantially as and for the purposes specified.
2. In a combination-padlock, the shell A, provided with partitions a' , having openings $a^2 a^3$ and central opening a^4 , and indicating disk or dial provided with shank C^4 , passing through opening a^4 , and nut C^6 and cover D, 40 having openings d' , coincident with the openings a^2 , and provided on its periphery with a screw-thread engaging the screw-thread on the interior of the shell A, substantially as and for the purposes specified.
3. In a combination-padlock, the shell A, provided with partition a' , provided with openings $a^2 a^3$ and central opening a^4 , and recess a^5 , cover D, having opening d' , coincident with openings a^2 , and having external 45 peripheral screw-thread d^3 , engaging an internal screw-thread a^5 of the shell A, and being provided with the recess d^2 , adjoining recess a^3 of partition a' of the shell, indicating dial C, provided with shank C^4 , engaging a 50 nut C^5 , located in recess $a^3 d^2$, said nut being provided with a transverse channel C^6 and containing a close-fitting key C^9 , whose upper edge extends above and beyond the surface of the nut C^5 , substantially as and for the 55 purposes specified.
4. In a combination-padlock, the shell A, having partition a' , provided with openings 60

$a^2 a^3$, and a cover D, provided with openings $d' d'$, coincident therewith, for the reception of the shanks of the staple, and having two 70 or more tumblers and tumbler-chambers, respectively, provided with openings $k' f'$ for the reception of the shanks of the staple, all of the said openings on one side of the padlock having a common axis, and the axes of 75 said openings on the two sides of the padlock being in a plane passing to one side of the axis of the shank C^4 , substantially as and for the purposes specified.

5. In a combination-padlock, the openings 80 formed by the concave recesses f' of the tumblers and the opposing concave recesses k' of the chambers for the reception, respectively, of the respective shanks of the staple, the axes of these openings being in a common 85 plane passing to one side of the axis of the padlock, substantially as and for the purposes specified.

6. In a combination-padlock having two or more tumblers, the tumbler consisting of an 90 annular ring F, provided with partly-concave depressions $f' f'$ in its periphery, and provided with niches or depressions $f^2 f^2$, formed in the interior wall of the said ring and bearing figures or other characters for setting the 95 combination, and the disk having a suitable abutment for engaging the stud or carrier operated by the shank C^4 , the said disk being provided with a stud or boss n^4 , received into any one of the niches or depressions f^2 100 of the annular ring when the said disk N is combined therewith, substantially as and for the purposes specified.

7. In a combination-padlock having two or more tumblers, the tumbler consisting of the 105 annular ring F, provided with niches or depressions $f^2 f^2$, formed in the inner wall of the said ring and bearing figures or other characters for setting the combination, and the disk having a suitable abutment for engaging the stud or carrier C^5 of the shank C^4 , the said disk being provided with the stud or boss n^4 , received into any one of the niches or depressions f^2 110 of the annular ring when the said disk N is combined therewith, substantially as and for the purposes specified.

8. In a combination-padlock, the combination of the shell A, having partition a' , provided with recess a^3 and central opening a^4 , and cover D, arranged to screw within said 120 shell and having openings $d' d'$, provided with recess d^2 , and engaging dial C, forming one end of the padlock, and provided with central shank C^4 , having a stud or carrier C^5 fixed thereon, and the tumbler-chambers arranged upon the pins $k^2 k^2$ and provided with the concave depressions $k' k'$, and tumblers having exterior concave depressions f' , and each consisting of an annular ring, as F, and the central disk N, whose stud n^4 engages any one of a series of niches at the inner edge of the ring F, and shank C^4 , having a notch in its upper or free end and passed through the openings $f' k'$ and through the 125 130 135

opening a^4 of the partition a' of the shell, and engaging at its upper end with a nut C^5 , provided with a channel, as C^6 , into which and into the notch of the shank is received a locking key or pin C^9 , and the staple B , whose shanks $b' b'$ are respectively received into the openings a^2 of the partition a' and the openings $f' k'$ of the tumblers and adjacent tumbler-carriers, substantially as and for the purposes specified.

9. In a combination-padlock, the combination of the shell A , having partition a' , provided with recess a^3 and central opening a^4 , and cover D , arranged to screw within said shell, and having openings $d' d'$, provided with recess d^2 and index-dial C , forming one end of the padlock and provided with central shank C^4 , having studs or carriers C^5 fixed thereon, and the tumbler-chambers arranged upon the pins $k^3 k^2$ and provided with the concave depressions $k' k'$, and tumbler-chambers having exterior concave depressions f' , and consisting of an annular ring, as F , and

a central disk N , whose stud n^4 engages any one of a series of niches at the inner edge of the ring F , the shank C^4 , passed through the tumblers and through the opening a^4 of the partition a' of the shell, and engaging at its upper end with the nut C^5 , provided with a channel, as C^6 , into which and into the notch of the shank is received a locking key or pin C^9 , and the staple B , whose shanks $b' b'$ are respectively received in the openings $f' k'$ of the tumblers and adjacent tumbler-carriers, the said openings for the reception of the shanks of the staples being so located with reference to the axis of the padlock proper that a plane passing through the axes of the said openings will lie to one side of the axis of the padlock, substantially as and for the purposes specified.

HENRY H. DANIELS.
